STRAND HANDLING APPARATUS

Erwin E. Franz, Cranford, N. J., assignor to Western Electric Company, Incorporated, New York, N. Y., a corporation of New York

Application March 11, 1936, Serial No. 68,283

5 Claims. (Cl. 242—4)

This invention relates to strand handling apparatus and more particularly to apparatus for winding strands on toroidal cores.

In various branches of the electrical arts, particularly in such as deal with the recording, reproduction and transmission of sound there is use for electromagnetic circuits involving compact and efficient inductive devices in the form of toroidal or doughnut shaped cores of magnetic material having coils of electrical conductors wound thereon. Some such cores are made integral throughout and the windings placed thereon by threading the successive turns of conductor through the central hole in the coil.

10 An object of the present invention is to provide apparatus for winding a strand on a toroidal core in successive turns each passing through the central aperture of the core.

The invention contemplates, in one embodiment thereof, an apparatus comprising means to hold a toroidal core to be wound, a substantially rectilinear shuttle to hold and carry a supply of strand to be wound on the core, means to carry the shuttle and the strand in a closed loop path 25 passing through the aperture of the core, and coacting means to apply the strand thus looped through the core in tight and properly disposed and located turns about the core.

Other objects and features of the invention will appear from the following detailed description of an embodiment thereof in apparatus for winding a strand on a toroidal core, taken in connection with the accompanying drawings in which the same reference numerals are applied 35 to identical parts in the several figures, and in which

Fig. 1 is a broken, schematic plan view of an apparatus embodying the invention with the lid removed;

40 Fig. 2 is an enlarged broken section on the line 2—2 of Fig. 1;

Fig. 3 is a detached, broken, perspective view of the moving parts shown in Fig. 2 and associated parts;

45 Fig. 4 is an enlarged detached view in longitudinal central section of the shuttle;

Fig. 15 is a detached broken perspective view 10 of the shuttle drive at the winding point;

Fig. 16 is a view similar to Fig. 1 of another modified form;

Fig. 17 is a section on the line 17—17 of Fig. 16; and 15

Fig. 18 is a section on the line 18—18 of Fig. 1.

In the embodiment of the invention disclosed in Figs. 1 to 11 inclusive, the apparatus is assembled and supported on a tabular base member 25 which may be supported by any appropriate means not shown, such as legs or a pedestal or brackets or the like. This base member is preferably an appropriately formed and machined casting or forging of suitable material, iron, steel, brass, or the like. On the base 25 rests 20 a similarly tabular cover member 26, which is formed with a large central roughly ellipsoidal opening 27. The tabular cover member may be one piece, or for convenience in manufacture, may be made in two or more parts, as may also 30 the base member 25. A sheet metal lid 28 may be provided and may cover the entire apparatus or may be formed as shown with a central opening to match the opening 27. The members 25, 26, and 28 may be secured together in any suitable 35 fashion as by screws, bolts, pins, clamps, or the like, not shown.

The base 25 and the cover 26 are formed with matched coacting grooves 29 and 31 respectively (Fig. 2) which together form a shuttle guide 40 channel 30 having a nearly closed cross section interrupted by a continuous slot 32 along that side of the channel which is toward the opening 27. The channel 30 runs in an elongated closed figure with parallel straight sides joined by arcuate ends. In the straight portions of the channel, its cross section is substantially circular, but in the arcuate ends it is broadened in the horizontal plane to allow the rigid, straight shuttle 40, which travels in the channel, to swing around the 45 curves.

The base 25 is also formed with vertically disposed slots 33 and 34 which coincide in position and communicate with the bottom of the channel 30 around the arcuate parts and along portions 50 55

of the straight parts of the channel. Each of the slots 33 and 34 is a closed loop disposed roughly in a double arch with the portion along the inner side of the arch coinciding in position 5 as described with part of the channel 30. There is a gap at each side of the machine between the opposed feet of the slot loops.

The gap at the right side (Fig. 1) is bridged by a slot 36 formed in the cover 28 and communicating 10 with the channel 30 through the top thereof, along a part of the slot 36. The slot 36 extends as an elongated loop, coinciding in position in part with the slots 33 and 34 and with the channel 30.

15 In the gap at the left side the members 25, 26, and 28 are cut away in a triangular recess 31 communicating at its inner end with a short parallel walled passage 38 which in turn opens into a roughly octagonal aperture 39 in the base 25. 20 The channel 30 is interrupted by the passage 38. A clamping device generally indicated at 23 is supported by means not shown in the recess 31 and serves to hold a toroidal core 24 in position to be wound. The details of structure and functioning of the device 23 are irrelevant to the present invention and so are not disclosed here. A satisfactory device for the purpose is disclosed in U. S. Patent 1,994,661 issued March 19, 1935. It suffices to remark here that the device is movable 25 to distribute the successive turns upon the core circumferentially thereof.

A shuttle, generally indicated at 40 and shown in detail in Figs. 4, 5, and 6, is located in the channel 30, the channel and shuttle being relatively so proportioned that the shuttle may slide freely in and be guided by the channel. The shuttle comprises a hollow cylindrical body 41 of metal, or of suitable composition such as artificial resin, and a pair of end plugs 42 and 43.

40 The front plug 42 is fastened into the body 41 by a pin 44, and is formed with a transverse bore in which is housed a sliding latch 45 provided with a spring 46, the spring pressed latch 45 serving to removably retain a correspondingly 45 notched bobbin stem 47 in the head 42. The body 41 is formed with a perforation 48 opposite the upper end of the latch 45, through which an appropriate tool may be thrust to depress the latch and release the bobbin stem when desired.

50 The bobbin stem 47 has one head 48 rigidly secured near its forward end by a pin 49 the head being formed with one or more recesses 50 to receive driving members when the bobbin is to be filled.

55 The rear plug 43 is removably secured in the body 41 by a latch member 51 mounted in an appropriate transverse bore in the plug and pressed outwardly by a spring 52. This plug is also formed with an axial passage 53 to permit

60 strand 22 to pass from the bobbin out the rear end of the shuttle. Each of the plugs 42 and 43 is further formed with an external circumferential driving slot 53 and 54 respectively.

Returning now to the base member 25 of the 65 apparatus, each of the slots 33 and 34 communicates along its lower edge with a correspondingly located passage 55 and 56 respectively which runs through the body under the corresponding slot; and the slot 36 communicates along its upper 70 edge with a similar passage 57 running through the cover 26.

Sprocket chains 58, 59, and 60 are housed in the passages 55, 56, and 57 respectively. The sprocket chain 58 runs over four idler sprockets 75 61, 61 and is driven by a sprocket 62 on the shaft

63. The chain 58 runs over three idler sprockets 64, 64 (two broken away in Fig. 1), drives the shaft 65 through the sprocket 66, and is driven by the sprocket 67 from a suitable motor 168. The shaft 65 drives the shaft 63 through a chain 68. 5 The chain 60 is driven by the sprocket 69 on the shaft 63 and runs over an idler sprocket 70.

The chains 58 and 60 carry, at predetermined intervals along the same, upstanding pins 71 extending up therefrom through the slots 33 and 34 into the channel 30 in such a way that one and only one of these pins at a time may engage either in the slot 53 or the slot 54 of the shuttle 40. The chain 60 is provided with similar pins 72 extending similarly downwardly therefrom 15 through the slot 36 into the channel 30 also to engage with the slots 53 or 54.

The chain 68 runs also over and drives a sprocket 73 on a shaft 74 (Figs. 1, 10, and 11) journaled vertically in a bracket 75 secured in 20 any suitable way as by bolts 76 to the base 25. The upper arm 71 of the bracket is also formed as a stationary cam member with a cam groove 78 formed therein. A gear 79 is freely rotatable on the shaft 74 and is driven by a link 80 pivotally attached to the gear and also to an annular driving member 81 encircling the shaft 74. A second driving member 82 is mounted on and keyed to the shaft and drives the member 81 through a pivot pin 83 mounted in both members 30 81 and 82. The member 81 is also provided with a cam pin 84 whose enlarged head slides in and is guided by the cam groove 78. The gear 79 is thus driven by the continuously rotating shaft 74 with a cyclically intermittent and cyclically 35 varying motion.

The gear 79 drives a horizontal shaft 85 through a gear thereon as shown, which shaft extends under the inner edge of the aperture 39 in the left side of the machine base, where it drives 40 a gear 86 and thereby a pair of other gears 87, 88 through intermediate idlers as shown (Figs. 7, 8, and 9), so that gears 86, 87, and 88 run in the same direction as one passes around the circumference of the aperture 39. 45

The tops of the gears 86, 87, and 88 lie a little below the axial plane of the channel 30 and support the arcuate body of an applicator generally indicated by the numeral 90, and formed on its under side with gear teeth 89 to match 50 and engage with the teeth of the supporting gears. The body of the applicator consists of two, arcuately trough shaped halves 91 and 92, arcuate also in cross section, together forming an incomplete circular toroid of circular cross 55 section. The two halves are hinged together at 93, 93, and enclose a chamber of generally toroidal form.

Beginning now at the left upper end of the applicator chamber (Fig. 7), there is therein a 60 wheel 94 mounted on a block 95 which is urged toward the right by a compression spring 96. The periphery of the wheel 94 is formed with a tapered and blunted edge as shown in Fig. 9, which mates with the grooved edge of a sheave 65 97 mounted on a stationary pivot. Next and spaced slightly from the sheave 97 is a similar, grooved and fixedly positioned but rotatable sheave 98, followed at a small space by another grooved, fixed and rotatable sheave 99. Further 70 along, another grooved sheave 100 is mounted in a block 101 balanced between springs 102 and 103. There is a short slot 104 in the outer periphery of the applicator body opposite the contact of the wheel 94 and sheave 97, and a longer slot 75

106 in the inner body periphery running about from the wheel 84 to the block 101.

In operation, the bobbin 47, 48 is filled with strand to be wound on a toroidal core 24 held in the clamp 23 and the bobbin seated in the shuttle 40. The end of the strand is threaded through the applicator from the shuttle as shown in Fig. 7 and is secured to the core. The shuttle is introduced into the channel 30 across the gap 10 at 38 and through the aperture of the core as indicated in Fig. 1. One of the pins 71 of the belt 58 is engaged in the slot 53 of the shuttle. To do this, it is preferable that portions of the cover 28 on either side of the winding point be made separate and removable or hinged to the remainder of the cover.

The motor 168 is then started to drive the gear 87 counterclockwise, thus driving the chain 58 in the direction of the arrows applied thereto. 20 The chain 58 draws the shuttle down, around the lower part of the channel 30 and up on the right hand side until, as indicated in Fig. 3, at a predetermined moment one of the pins 72 of the chain 60 enters the top of the slot 54 at the 25 rear of the shuttle. A moment later the pin of the chain 58 leaves the shuttle to pass off around the sprocket 66. The chain 60 then pushes the shuttle along until it is in the position shown in dotted lines in Fig. 3 when one of the pins 30 71 of the chain 58 enters the under part of the slot 54 at the rear of the shuttle and a moment later the pin on the chain 60 disengages from the shuttle and passes away over the sprocket 69. This transfer from chain to chain is necessary to change the drive of the shuttle from the 35 front slot 53 to the rear slot 54 in anticipation of pushing the shuttle through the core 24 again, which is done shortly thereafter by the chain 58. Then when the shuttle is again in the position 40 shown in Fig. 1, another pin 71 on the chain 58 will enter the forward slot 53 while the pin on the chain 58 leaves the slot 54 and the above cycle is repeated.

Meantime the cam track 78 is so formed that 45 the applicator remains in the position shown in Fig. 1 from a time before the front of the shuttle reaches it until a time after the rear of the shuttle has passed. Then the cam sets the gears 86, 87, and 88 and therewith the applicator, in motion until the applicator has made one revolution through the core and has wrapped the loose loop of strand formed about the core by the shuttle into a tight turn about the core. The strand as it is tightened thus about the core is tensioned by the system of sheaves and springs 50 within the applicator. In particular also the sheave 100 balanced between the springs 102 and 103 serves to take up and give out strand alternately to compensate for the varying distance of the sheave 99 from the core as the applicator 55 revolves.

The modified form of the apparatus shown in Figs. 12, 13, 14, and 15 performs the same operation in substantially the same way, but here the 60 chains 58, 59, and 60 and the guide channel 30 of the previously described machine, are replaced by a single flexible belt 258 having the cross section shown at the top of Fig. 14 and having driving pins 259 whereby it may be positively driven from one of a correspondingly notched or toothed pair of twin wheels 267 driven by the motor 268. The upper wheel 267 is an idler hung from the under side of the cover 28, and the lower wheel 267 is the actual driver. 70 There is a clear gap between the two wheels over

their entire neighboring faces to allow the strand 22 to pass freely between them.

The belt 258 is formed as shown with a flat back 261 to run on the various supporting and driving wheels, and with a shuttle gripping portion 262 having a longitudinal groove 263 therein. The groove has the cross-sectional contour of a trifle more than half a circle of such dimension as to fit closely around and grip the cylindrical shuttle 240 frictionally and so drive it without 10 the need for driving pins such as 71. In passing over the idler sheaves nearest the core 24, as shown in Fig. 15, the lips 264 open because of the bending of the belt to release the shuttle above and to grip it again below the core, before and 15 after passing therethrough.

The shuttle 240 is made with an elastically flexible body 241, and the strand is wound on a removable core pin (not shown) which is removed after the bobbin with its stub core pin is placed 20 in the body 241. Thus the shuttle will conform to the peripheral contour of the twin wheels 267 while passing therover.

The third disclosure in Figs. 16 and 17 shows the modifications necessary to use the flexible belt of 25 Fig. 12 with the rigid shuttle of Fig. 1. A fixed twin cam or guide 205 is mounted to extend between the twin wheels 267, against which guide the inner side of the body of the shuttle slides as the belt passes over the wheels and grips the ends 30 only of the shuttle.

In many machines of the prior art for winding on toroidal cores there is a toroidal shuttle interlinked with the core to be wound and rotating in such fashion that the entire path of each 35 part of the shuttle lies always within the body of the shuttle. The shuttle is a ring and while one part of it is passing through the hole in the core the diametrically opposite part is passing through the plane of the core outside the core and in the 40 opposite direction. It is characteristic of the present invention that while the shuttle is passing through the aperture of the core the entire shuttle is moving unidirectionally as to all parts thereof. There are no two parts moving simultaneously 45 in opposite directions. The prior toroidal shuttles remain stationary in position although rotating there. The present shuttle is transported bodily as a whole.

The embodiment of the invention herein disclosed is illustrative only and may be widely departed from and modified in many ways without departing from the spirit and scope of the invention as pointed out in and limited only by the appended claims.

What is claimed is:

1. In an apparatus for winding strand on a toroidal core, means to hold a toroidal core to be wound, a pair of sheaves positioned with the core therebetween, a shuttle to hold a supply of strand, 60 flexible means passing over one of the sheaves and positioned to engage the shuttle and having means thereon to insert the shuttle into the core and then release the shuttle after it has moved into the core, and flexible means passing over the other sheave and positioned to engage the shuttle and having means thereon to couple to the inserted shuttle and withdraw the same from the core.

2. In an apparatus for winding strand on a 70 toroidal core, means to hold a toroidal core to be wound, a pair of sheaves positioned with the core therebetween, a shuttle to hold a supply of strand, flexible means passing over the sheaves and positioned to engage the shuttle and having means 75

- thereon to insert the shuttle into the core and then release the shuttle after it has moved into the core and to couple to the shuttle again and withdraw the same from the core.
5. 3. In an apparatus for winding strand on a toroidal core, means to hold a toroidal core to be wound, a shuttle to hold a supply of strand, means positioned adjacent to the core on both sides thereof to insert the shuttle into the core 10 from one side thereof and to release the shuttle after it has moved into the core and to couple to the shuttle again on the other side of the core and to withdraw the shuttle from the core and transport it bodily and as a whole around the 15 core and outside the same and to the first side thereof again.
4. In an apparatus for winding strand on a toroidal core, means to hold a toroidal core to be wound, a shuttle to hold a supply of strand, an 20 endless belt having means thereon to grip and to

release the shuttle, means to guide the belt to the core at one side thereof to insert and release the shuttle therein, and means to guide the belt to the core at the other side thereof to grip and withdraw the shuttle therefrom.

5. In an apparatus for winding strand on a toroidal core, means to hold a toroidal core to be wound, means to define a looped path passing through the core, a shuttle to hold a supply of strand, and means to move the shuttle along the 10 path comprising an endless flexible member disposed in part along a part of the path and provided with means to couple to and uncouple from the shuttle, a second endless flexible member disposed in part along another part of the path 15 and provided with means to couple to and couple from the shuttle, and a third similar flexible member to bridge a gap between the first and second members.

ERWIN E. FRANZ. 20
